UNITED STATES PATENT OFFICE.

CHARLES W. LANDAUER, OF GRAND RAPIDS, MICHIGAN.

DESIGN FOR A BASE FOR SPRING-LATCH DEVICES.

46,570.

Specification for Design.

Patented Oct. 20, 1914.

Application filed April 27, 1914. Serial No. 834,846. Term of patent 14 years.

To all whom it may concern:

Be it known that I, CHARLES W. LANDAUER, a citizen of the United States, residing at Grand Rapids, in the county of Kent and State of Michigan, have invented a new, original, and ornamental Design for a Base for Spring-Latch Devices, of which the following is a specification, which, taken in connection with the accompanying drawing, fully discloses the essential features of the said design.

In the drawing, Figure 1 is a perspective view of the base and showing the design thereof. Fig. 2 is a side view of the base, a spring latch member used therewith being shown in dotted outline.

The base is comprised of securing parts or ears 1 extending outwardly in opposite directions from the central vertical member 2 which includes spaced apart sides 3 having ends bent inwardly toward each other at their front ends as shown at 4 and which at their rear ends are connected by an integral portion or section 5 rounded and formed as a partial cylinder within which the spring used with such bases when the latch arm is

applied thereto may be received and concealed.

It is the main and essential characteristic or feature of this design that the base have its vertical member closed at each end, concealing all mechanism placed within the said member and presenting a pleasing appearance without disclosing edges and interior construction as heretofore.

What I claim is,—

The ornamental design for a base for spring latch devices comprised of a central member having spaced apart sides and inclosing ends, one end being rounded and enlarged to form a partial cylindrical member, and attaching ears extending to either side of the central member, as shown and described.

In testimony whereof, I have hereunto affixed my signature in the presence of two witnesses.

CHARLES W. LANDAUER.

Witnesses:

FRANK E. LIVERANCE, Jr.,
L. E. CARROLL.
